J. P. Walker
ATTORNEY.

UNITED STATES PATENT OFFICE.

WILLIAM FOLLET, OF DAYTON, OHIO, ASSIGNOR TO THE CRAWFORD, McGREGOR AND CANBY COMPANY, OF DAYTON, OHIO, A CORPORATION OF OHIO.

HEEL GAUGE.

Application filed June 20, 1921. Serial No. 478,952.

To all whom it may concern:

Be it known that I, WILLIAM FOLLET, a citizen of the United States, residing at Dayton, in the county of Montgomery and State of Ohio, have invented certain new and useful Improvements in Heel Gauges, of which the following is a specification.

My invention relates to measuring instruments and more particularly to heel gauges for shoe lasts.

It is customary for the shoe manufacturer to supply the last maker with a templet or form or in some instances with a sample last disclosing the particular curvature of the heel of the last or shoe which has been adopted as a standard by such manufacturer. This curve varies somewhat among different shoe manufacturers. Some manufacturers prefer a heel curve of considerable depth, while others adopt one of less degree. These curves are not circular but are irregular curves, and in different instances, the point of greatest depth varies among different manufacturers. Moreover, this standardized curve is usually supplied for only one size of lasts. The size 4 last is usually adopted as the standard and lasts of other sizes are made to agree therewith except for certain modifications due to the increased or decreased sizes.

It is customary to maintain the standardized curve so that whatever the size of the last the heel curve will be the same, in contour or outline. The present invention pertains to the standardization of the heel curve for different sizes of lasts or a system of grading shoe lasts in which this curve is tilted inward or outwardly about an imaginary point at the apex of the base angle of the last heel formed by the juncture of the heel curve and the bottom of the heel to predetermined degree for each different size of last. That is to say, using the intersection of the heel curve with the bottom of the last, as a center this curved outline is tilted inwardly or outwardly with each variation of size. An arbitrary standard is employed wherein the variations of this heel contour varies to and

mately one thirty-second of an inch for each variation of size, measured at the top of the heel curve.

It is quite important that this curvature be accurately determined. If a simple templet is employed to gauge the heel curve, such templet should always be applied at the same angle with the bottom of the last, or in the same relation with the last body for each last of a given size. If the pitch of the curve is slightly greater in one last than in the other last of a given pair, one of the shoes made over such a last will be tight in the heel and will bind and annoy the foot of the wearer.

The object of the present invention is to afford a simple economical and accurate gauge by which not only the curvature or contour of the heel outline may be determined, but also the predetermined pitch or angular relation of the heel curve with the sole or bottom of the lasts of different sizes determined. This is important in order that all lasts of a given size may be exact duplicates of each other in this respect and in order that lasts of different sizes may agree accurately with the shoe uppers for such sizes as graded upon the leather grading machine.

A further object of the invention is to provide in such a gauge adjustment means whereby the gauge may be readily varied to accommodate lasts of different sizes, and for accurately determining the pitch of the heel curve for any given size of last.

With the above primary and other incidental objects in view as will more fully appear in the specification, the invention consists of the features of construction, the parts and combinations thereof and the mode of operation or their equivalents as hereinafter described and set forth in the claims.

Referring to the drawing, wherein is shown the preferred, but not the only embodiment of the invention, Fig. 1 is a perspective view of the adjustable heel gauge applied to the heel of a last, illustrating the mode of application, and the gauging point. Fig. 2 is a side elevation of the gauge, show-

from the standarized size 4 last, approxi-

ing by dotted lines, the variation of adjustment of the heel curve template. Fig. 3 is a detail view of a detachable or interchangeable heel template for use in the gauge shown in Fig. 1. Fig. 4 is a diagrammatic view illustrating the variations of pitch of the heel curve for different sizes of lasts. The variations of sizes have been very much exaggerated in this view for purpose of illustration.

Like parts are indicated by similar characters of reference thruout the several views.

Referring to the drawings, 1 is the heel portion of a shoe last, the heel curve or contour 2 of which is to be engaged by the instrument forming the subject matter hereof. As before stated, this outline or curvature is predetermined by the shoe manufacturer who will use the last. This curvature will be produced upon a metal plate or template 3. Different templates having outline or contour curves of different degrees will be provided for different manufacturers, or for different styles of lasts. The heel curve of the last is then made to agree with this curvature. In the form of device shown in Fig. 1, this template or form plate 3 is detachably mounted in the holder wherein it is adjustable in relation with other gauge points to accommodate it to different sizes of lasts. This holder device comprises a plate 4, to which is pivoted at 5 an oscillatory adjustable bar 6. The bar 6 is recessed or slotted to receive the detachable template 3 which is secured in place by the clamp screw 7 or other suitable means. Mounted in suitable lugs or studs 8 and 9 on the lower ends of the main plate 4 and adjustable bar 6 is an adjusting screw 10, by which the bar 6 is adjusted to and fro about its pivotal connection 5. The bar 6 and with it the template 3 carried thereby are held in their adjusted position by means of a second clamp nut 11, engaging thru an arcuate slot 12 in the bar 6. The main plate 4 may be graduated as at 13 to indicate different degrees of pitch of the heel curve or different sizes of lasts. If such graduated scale is employed, the adjusting screw is operated to oscillate the template carrying bar 6 into registry with the desired indication. This will cause the template 3 to assume a predetermined angular relation with the gauge point 14 on the plate 4 which in operation bears upon the sole bottom of the last heel, and the center of oscillation 5 which forms a second gauge point to be brought into registry with the bottom angle of the last heel. The gauge is applied to the heel of the last with the gauge point 14 bearing upon the bottom of the last and the pivotal point 5 at the juncture of the heel curve and last sole or the bottom angle of the last heel, whereupon if the last is accurately contoured the heel curve will agree

exactly with the curvature of the template 3. If the heel curve does not accurately agree, the last is not properly proportioned or made or the last is of a different size. For each variation of one size of last, the top end of the template curve is tilted outwardly or inwardly according to the increase or decrease of the last size approximately one thirty-secondth of an inch, while the lower end of the heel curve or template plate remains constant at the point 5, coincident with the base angle of the last heel formed by the juncture of the heel curve with the bottom of the last.

In lieu of employing the series of graduations 13, for adjusting the gauge to different sizes of lasts, the adjusting screw 10 may be threaded on such pitch that exactly one rotation of the adjusting screw will be required to vary the template the distance of one last size. This in practice is a very convenient mode of measurement. In lieu of the clamp nut 11 the adjusting screw 10 may be provided with a nut 15, which will serve as a lock nut to secure the adjusting screw against movement and so hold the gauge in any desired position, of adjustment.

While a gauge such as shown in Fig. 1 employing detachable or interchangeable heel template 3 is desirable for inspection work where the operator may have occasion to change frequently from one style or type of last to another, the form of non-changeable or permanent gauge shown in Fig. 2 is preferred for production purposes. In this form of device the template curve 2 is produced directly upon the oscillatory blade or bar 6. Hence the bar or blade 6 instead of being merely a carrier for the template as in Fig. 1, becomes the template per se. Otherwise the operation of the device is substantially as before described.

Referring to Fig. 4 and assuming that the solid line contour is that of the standardized curve for a number 4 last, the pitch of this curve will be inclined inwardly as at X for lasts of smaller sizes, or will be inclined outwardly as at Y as the last sizes increase. The adjustment of the blade or bar 6 by means of the adjusting screw 10 varies the template curve to the various pitch positions shown in Fig 4. In any position there are three gauge points to wit: the point 14, at the forward corner of the main plate 4, the point 5 which is also the center of oscillation, which upon application to the last is brought into agreement with the juncture of the heel curve and last sole or the bottom angle, and the upper end of the template which is brought into bearing against the juncture of the heel curve and top of the last or the top angle, whereupon if the last is properly contoured, the curvature thereof must agree accurately with that of the

template. The herein described method of grading shoe lasts by tilting the heel curve forwardly or rearwardly to different predetermined degrees in accordance with different sizes of lasts, is described in and made the subject matter of a divisional application for Letters Patent, Serial No. 33,136, filed May 27, 1925.

From the above description it will be apparent that there is thus provided a device of the character described possessing the particular features of advantage before enumerated as desirable, but which obviously is susceptible of modification in its form, proportions, detail construction and arrangement of parts without departing from the principle involved or sacrificing any of its advantages.

While in order to comply with the statute the invention has been described in language more or less specific as to structural features, it is to be understood that the invention is not limited to the specific details shown, but that the means and construction herein disclosed comprise but one of several modes of putting the invention into effect, and the invention is therefore claimed in any of its forms or modifications within the legitimate and valid scope of the appended claims.

Having thus described my invention, I claim:

1. In a heel gauge for shoe lasts, two interpivoted members capable of relative adjustment about their pivotal connection, one of the members being engageable with the bottom of the last heel, the other member having an arcuate edge agreeing with the predetermined contour of the back of the last, the pivotal connection being located substantially at the intersection of the gauge faces of the respective members, and means to retain the members in their adjusted relation.

2. In a heel gauge for shoe lasts, a supporting member engageable with a predetermined portion of the last to be gauged, and an arcuate template carried thereby and adjustable to various positions angular to said member to vary the pitch of the template curve with the supporting member.

3. In a heel gauge for shoe lasts a member engageable with a predetermined portion of the shoe last, and an arcuate heel template adjustable to different angular relations with the first mentioned member about a point coincident with the base angle of the last heel, when the gauge is applied thereto to agree with the heel pitch of lasts of different sizes.

4. In a heel gauge for shoe lasts an arcuate template agreeing with the predetermined contour of the last heel, and last engaging means in relation with which the template is adjustable to different angular relation about a center point corresponding

to the lower end of the heel curve of the last in accordance with variations of the sizes of different lasts.

5. In a heel gauge for lasts, an arcuate template agreeing with the predetermined rear outline of the last heel, and a support therefor engageable with a predetermined portion of the last in relation with which the template is adjustable to various angular positions about a point coincident with the juncture of the rear outline and bottom of the last heel when the gauge is applied thereto.

6. A gauge for lasts wherein a like rear outline curve of the last heel is maintained throughout a range of different sizes of lasts, the pitch of such curve in relation with other parts of the last varying with variations of size of the lasts, characterized by an arcuate template agreeing with the predetermined rear contour of the last heel, last engaging means, said arcuate template being capable of oscillatory movement about the lower end of the last heel contour as defined by said template, and means for maintaining the template in adjusted relation with said last engaging means.

7. In a heel gauge for shoe lasts, a main support having gauge points thereon, a blade pivotally mounted thereon, a template detachably carried by the blade, an adjusting screw interconnecting the pivoted blade and support and means for locking the blade to maintain the template in different positions of oscillatory adjustment in relation with the gauge points of the support.

8. In a heel gauge for shoe lasts, two interpivoted members, one having gauge points thereon for engagement with the last, the other being curved to agree with the rear contour of the last heel, an adjusting screw for varying the relative adjustment of said member, one of said members having scaling means by which the variation of adjustment may be determined in predetermined units of measurement.

9. In a heel gauge for shoe lasts, two interpivoted members, one of the members having gauge points thereon for engagement with the last, a detachable template carried by the other member the contour of which agrees with that of the predetermined outline of the last heel, means for relatively adjusting said members to measured degrees of pitch of the template in relation with the gauge points of the first mentioned member to correspond with the heel pitch of lasts of different sizes.

10. Means for gauging the heels of shoe lasts wherein the pitch of the heel curve in relation with other portions of the last varies with variations of last sizes, comprising two relatively adjustable members, one of which has gauge points thereon for engagement with the last, the other of which is curved

to agree with the predetermined outline of the last heel and means for relatively adjusting said curved member to various positions angularly disposed in relation to said first named member and corresponding to predetermined relative degrees of pitch of the heel curve in relation with the portions of

the last engaged by the gauge points of the first mentioned member to determine the heel pitch of lasts of different sizes.

In testimony whereof, I have hereunto set my hand this 11 day of June A. D. 1921.

WILLIAM FOLLET.
